UNITED STATES PATENT OFFICE.

GEORGE W. LANCASTER, OF RICHMOND, VIRGINIA.

SAFETY-SHUTTER.

1,179,328.

Specification of Letters Patent. Patented Apr. 11, 1916.

Application filed November 24, 1914. Serial No. 873,791.

To all whom it may concern:

Be it known that I, GEORGE W. LANCASTER, a citizen of the United States, residing at Richmond, in the county of Henrico and State of Virginia, have invented certain new and useful Improvements in Safety-Shutters; and I do hereby declare the following to be a full, clear, and exact description of the invention, such as will 10 enable others skilled in the art to which it appertains to make and use the same.

This invention relates to improvements in shutters and resides in the provision of an attachment comprising a frame that is to be secured to a window frame in such manner that it may be easily swung into and out of operative position and locked in operative position, vertically movable shutters being mounted within the frame, also a screen 20 ranged in the rear of the shutters.

One of the principal objects of this invention is to provide easily operable and effective means for locking each of the shutters in operative position, said means being 25 operable from the inside of the window and serving in combination with the shutters, which are preferably constructed of metal to provide a burglar proof window and prevent breaking or cracking of the panes by 30 high winds.

Another object is to provide a device of the character described which will be fire-proof, when locked in operating position, permit ventilation and at the same time 35 prevent entrance of rain into the room.

Another object is to provide a simple, inexpensive and effective safety shutter in the form of an attachment that may be easily and quickly attached to a window frame of 40 the ordinary construction without necessitating any material change in the construction of the frame to which it is attached.

Another and more specific object is to provide a shutter which includes a plurality of vertically movable slats and notched supporting elements for the slats, the slats to be pulled upwardly upon the notch supporting elements so constructed that when allowed to drop each slat will catch at a predetermined point upon the supporting element therefor and rest in forwardly and outwardly inclined position in equal spaced relation to the other slats.

The above and additional objects are accomplished by such means as are illustrated in the accompanying drawings, described

in the following specification and then more particularly pointed out in the claims.

With reference to the drawings, wherein I have illustrated the preferred embodiment of my invention as it is reduced to practice, and throughout the several views of which similar reference numerals designate corresponding parts, Figure 1 is a front elevation of my improved device showing it attached to a window, Fig. 2 is an end elevation of the frame for the shutter with one of the side plates removed showing the shutter construction and locking mechanism in position, Fig. 3 is a horizontal sectional view showing the supporting mechanism for the slats of the shutter and locking means therefor, Fig. 4 is a fragmentary sectional view taken through the top of the window and shutter frame, showing a part of the operating means therefor, Fig. 5 is a fragmentary vertical sectional view taken through the lower part of the window and shutter frame showing the means for operating the locking means on the inside of the window, Fig. 6 is a side elevation of a slightly modified form of my invention showing it broken away, Fig. 7 is a fragmentary horizontal sectional view of the modified form, and Fig. 8 is a detail 85 plan view of the type of slat used in the modified form.

Referring to the drawings by characters of reference, A designates as an entirety a window frame of the ordinary construction 90 to which is secured my improved safety shutter designated B as an entirety.

The safety shutter B comprises a rectangular metallic frame 1 that is hingedly secured as at 2 to the window frame A, the 95 hinges being arranged upon the inside so that removal thereof from the outside of the window is prevented. The frame 1 comprises vertical side bars 3 and 4 that are joined at their ends by top and bottom bars 5 and 6. The bars 3 and 4 are preferably channel-shaped in cross section and have their open faces opposed. The several bars comprising the frame 1 are preferably removably secured to one another and parts 100 of the side bars are removable so that access to the operating mechanism may be readily had.

Slidably mounted within the side bars 3 and 4 of the frame 1 are a plurality of metallic shutter slats 7 that are disposed in a horizontal plane and arranged to be moved

upwardly in engagement with one another at the upper end of the frame. Each of the shutter slats 7 is crimped longitudinally to provide reinforcing ribs 8.

5 The ends of the slats 7 are disposed within the U-shaped side bars 3 and 4 and are supported by suitable means which will be later more fully described. I provide a vertical guide rod 9 that is secured at its 10 ends to the bars 5 and 6 to the frame and extends through an elongated opening 10 formed in each of the slats 7. This rod 9 insures the slats moving into proper relative positions and prevents sticking thereof 15 in their sliding movement up or down.

Mounted within each of the side bars 3 and 4 is means to support the slats of the shutter which comprises a notched supporting plate 11. The side edges of the plate 11 20 are provided with notches forming supporting shoulders 12 and 13. The shoulders 12 on the forward edge of the plate 11 are disposed lower than the shoulders 13 on the inner edge of the plate and both shoulders 25 are inclined forwardly and downwardly so that the slats will be similarly disposed as will be later more fully described. Suitable brackets 14 serve to secure the plates 11 to the bars 4 and 5 in spaced relation to the 30 several walls of the bars. Each of the plates 11 decreases in width from its lower to its upper ends. Each of the slats 7 is provided adjacent to its ends on opposite sides with inwardly extending recesses 15 which provides extensions 16 that are slidable within the opposed faces of the bars 3 and 4.

The uppermost slat 7 is provided with recesses 18 in the ends thereof, that are of such size as to engage the shoulders 12 and 13 at 40 the uppermost part of the plate 11 and the uppermost slat is prevented moving downwardly. The next lower slat 7 has larger recesses 18 in the ends thereof and is designed to coöperate with the next lower pair 45 of shoulders 12 and 13. This next lowermost plate is permitted to be pulled upwardly from its normal position in spaced relation to the uppermost plate, into engagement with the uppermost plate. The lowermost 50 of the slats 7 is designed to be moved upwardly free of the shoulders 12 and 13 and is limited in its downward movement by the lowermost pair of shoulders 12 and 13 only. It will thus be seen that the slats 55 may be pulled upwardly on the plates 11 into engagement with one another but when allowed to drop, each slat will be prevented further downward movement at a predetermined point so that the slats 7 are equidistantly spaced and inclined forwardly and 60 downwardly.

As a means for pulling up the shutters, pull cables or cords 19 and 20 are mounted on pulleys 21 carried in the upper ends of 65 the bars 3 and 4 of the frame, extend down-

wardly in the bars 3 and 4 respectively and are secured at their lower ends to securing plates 22 carried on the lowermost of the slats 7 and at the ends thereof. The cables are extended from the pulleys 21 horizontally within the upper frame bar 5 and around pulleys 23 carried centrally of the ends of the bar 5 and disposed in a horizontal plane. The cables after passing around the pulleys 23 extend inwardly horizontally 70 and are mounted upon pulleys 24 carried upon the inner portion of the window frame A adjacent the top thereof and are allowed to hang from the pulleys 24 so that ready access thereto may be had to effect the raising or lowering of the shutters. By grasping and pulling the cables 19 and 20 the slats of the shutters will be lifted upwardly and upon releasing of the cable, each slat will drop to its proper position upon the 75 supporting plates 11.

I provide a screen 25 of the ordinary foraminous material that is secured upon the inner faces of the frame 1 by suitable securing strips 26. This screen prevents particles of sand or pebbles being thrown through the slats during storms and enables the desired ventilation of the room. The strips 26 may be removed if desired and the screen 25 taken off of the frame. 80

As a means for locking each of the slats 7 in down position I provide locking means within each of the bars 3 and 4 which consists of a vertical rotary shaft 27 which carries a plurality of L-shaped locking arms 28. An arm is provided for each of the slats and arranged so that when the shaft is rotated in a certain direction, it will be moved over and in engagement with the adjacent end of the slats 7. It will thus be seen that 100 the slats 7 are prevented being moved upwardly within the frame. 105

Rotatably mounted within one of the horizontal frame members of the window frame is an operating rod 29, which is formed with an enlarged recessed head 30 at its outer end and being provided with an operating handle 31 disposed interiorly of the window frame and at its other end. A rotary shaft 32 is journaled in a suitable supporting 110 block 33 in the lower end of the bar 3 of the frame and is provided with a squared enlarged head 34 to extend within the recessed head 30 of the rod 29. The shaft 32 is provided with an upstanding crank arm 35 115 that is connected by means of a horizontally disposed plate 36 with the rotary shaft 27. When the rod 29 is turned rotation of the shaft 27 is had through the medium of the shaft 32, crank 35 and plate 36 carried by 120 the shaft 27. It will thus be seen that the slats may be easily locked and unlocked from the interior of the frame A. 125

With reference to the foregoing description and accompanying drawings, it will be 130

seen that I have provided a safety shutter attachment for windows that will be fire-proof and burglar proof and which may be easily moved bodily into and out of operative position and opened or the shutters pulled upwardly from the interior of the room or window frame, only. Any suitable locking means may be employed to lock the frame of the attachment to the window frame and so that the lock may be operated from the inside of the frame only.

Referring particularly to Figs. 7 and 8 wherein I have illustrated a modified form of the invention, the shutters are particularly designed for use in connection with double windows, a duplicate shutter arrangement being placed upon the lower shutters. The slats 37 are mounted in a rectangular frame consisting of vertical side bars 38 of substantially the same formation as the preferred form and locking means designated 39 as an entirety is provided for the slats, said locking means being the same as in the preferred form. I provide guide plates 40 and 41. The plate 41 is disposed at its lower larger end adjacent to the upper smaller end of the plate 40 and both of these plates are duplicates of the plates 11 in the preferred form and are provided with the shoulders 42. It has been found in order to confine the size of the slats for the shutters to an extent so as to render them capable of use in various kinds of windows, two sets of slats should be arranged one above the other when an extra high window is to be equipped.

To accommodate the slats of the lower plate 40 for sliding upwardly upon the upper plates 41, the slats 37 on the lower plate 40, are provided adjacent to their ends with transverse elongated slots 43 which are greater in length than the greatest width of the plates 41 and arranged to slidably receive the plates 41. The upper plates 40 are offset inwardly and have their lower ends spaced from the upper ends of the plates 40 so as to extend into the slots 43.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:

1. In safety shutters, a frame, a plurality of shutter slats, upstanding supporting plates, shoulders carried by said supporting plates, said slats mounted upon the support-

ing plates and engaging the shoulders thereon and arranged to be moved upwardly on said plates, said supporting plates increasing in width toward their lower ends, said slats having recesses of varying widths to 76 coöperate with the plates and engaging the shoulders thereon, whereby each slat rests upon the shoulders at a predetermined point.

2. In safety shutters, a frame, a plurality of shutter slats, upstanding supporting 75 plates, shoulders carried by said supporting plates, said slats mounted upon the supporting plates and engaging the shoulders thereon and arranged to be moved upwardly on said plates, said supporting plates increasing 80 in width toward their lower ends, said slats having recesses of varying widths to coöperate with the plates and engaging the shoulders thereon, whereby each slat rests upon the shoulders on the plates at a pre- 85 determined point and the slats are equidistantly spaced from one another, and means to lock the slats in operative position.

3. In safety shutters, a frame, a plurality of vertically adjustable shutter slats, means 90 to slidably support the shutter carried by the frame, means to move the slats upwardly in the frame, and means to lock the slats in operative position including a rotary shaft and locking arms carried by the shaft and 95 arranged to engage the upper faces of the slats.

4. In safety shutters, the combination with a frame including upstanding hollow members, of a plurality of vertically adjustable shutter slats having their ends disposed within the hollow members, supporting plates carried within the hollow members, shoulders on the supporting plates, said slats having recesses in the ends thereof to 100 receive said plates, said shoulders engaging and supporting the slats, rotary shafts within the hollow members and locking arms carried by the shafts arranged to engage the slats on the upper faces thereof to lock them 105 in operative position.

5. A safety shutter comprising a plurality of vertically adjustable slats, upstanding slat supports increasing in width toward their lower ends and staggered shoulders 115 on the vertical edges of the supports, said slats having openings of varying widths therein to receive said supports.

6. A safety shutter comprising a plurality of slats, slidably upwardly and downwardly 120 to open and close the shutter, relatively fixed means for supporting the slats in their closed position, said means spacing the slats from one another to provide ventilating openings throughout the entire length of 125 the shutter when the latter is closed and means for engaging the upper faces of the slats for locking the same against the said supporting means to hold the slats against upward movement. 130

7. A safety shutter of the class described including relatively flat slats provided at their end portions with recesses formed directly in the slats, said slats being slideable upwardly and downwardly to open and close the shutter, means for engaging the said recesses to guide the slats in their upward and downward movement, and relatively fixed means arranged at intervals for supporting the slats in their closed position, said means being arranged to space the slats from one another to provide ventilating openings throughout the entire length of the shutter when the latter is closed.
15. 8. A safety shutter including slats having recesses in the ends thereof and opposite recesses in the sides of the same, means for engaging the side recesses for guiding the slats in an upward and downward direction and means operating in the end recesses for supporting the slats in spaced relation when at the limit of their downward movement.
25. 9. A safety shutter including slats having recesses in their ends and provided also with transversely extending openings, means for guiding the slats in an upward and downward direction and means operating in the said recesses and openings for supporting the slats in spaced relation when at the limit of their downward movement.
35. 10. A safety shutter comprising a plurality of slats adjustable upwardly and downwardly to open and close the shutter and relatively fixed seats arranged in pairs for supporting the slats in their closed position, the pairs of seats being spaced apart to provide ventilating openings throughout the entire length of the shutter when the latter is closed and the members of each pair of seats being located at opposite sides of the median plane of the slats.
45. 11. A safety shutter comprising a plurality of slats adjustable upwardly and downwardly to open and close the shutter and relatively fixed seats arranged in pairs for supporting the slats in their closed position, the pairs of seats being spaced apart to provide ventilating openings throughout the entire length of the shutter when the latter is closed, and the members of each
- pair being located at different elevations to set the slats at an inclination.
12. A safety shutter comprising a plurality of slats adjustable upwardly and downwardly to open and close the shutter and relatively fixed seats arranged in pairs for supporting the slats in their closed position, the pairs of seats being spaced apart to provide ventilating openings through the entire length of the shutter when the latter is closed, the members of each pair being located at different elevations to set the slats at an inclination, and locking means for engaging the upper faces of the slats for holding the same in their closed position.
13. A safety shutter of the class described comprising a plurality of slats slideable upwardly and downwardly to open and close the shutter, guides extending along the shutter for guiding the slats in their sliding movement and spaced seats arranged in pairs for supporting the slats in their closed position and in spaced relation to provide ventilating openings throughout the entire length of the shutter, the members of each pair of seats being located at opposite sides of the guides.
14. A safety shutter of the class described comprising a plurality of slats slideable upwardly and downwardly to open and close the shutter, guides extending along the shutter for guiding the slats in their sliding movement and spaced seats arranged in pairs for supporting the slats in their closed position and in spaced relation to provide ventilating openings throughout the entire length of the shutter, the members of each pair of seats being located at opposite sides of the guides, and means for engaging each of the slats at the upper face thereof for locking the slats upon the seats, the shoulders or seats of each pair are located at opposite sides of the median plane of each slat so that the latter is firmly supported in its closed position.
- In testimony whereof I affix my signature in presence of two witnesses.
- GEORGE W. LANCASTER.
